NEW YORK.

COMBINED TYPE-WRITING AND COMPUTING MACHINE

1,247,304.

Specification of Letters Patent. Patented Nov. 20, 1917.

Application filed August 26, 1911. Serial No. 646,133.

To all whom it may concern:

Be it known that I, FRED F. MAIN, a citizen of the United States, residing in Chicago, in the county of Cook and State of Illinois, have invented certain new and useful Improvements in Combined Type-Writing and Computing Machines, of which the following is a specification.

This invention relates generally to that class of combined typewriting and adding machines in which computing devices are set up by the numeral keys of the typewriter, and subsequently rotation is effected of the computing wheels, each to an extent determined by the setting of the computing devices by the numeral keys, thus registering the numbers on the computing wheels. The carriage of the typewriter is connected to the computing mechanism in a manner to determine the denomination of the computing device which is set by any key. A machine of this general description is illustrated in pending application No. 466,836, filed December 10, 1908; in my Patent No. 1,157,884, dated October 26, 1915, and in the patents to J. Frank Allard, No. 1,178,438, dated April 4, 1916, and Frederick A. Hart, No. 1,190,233, dated July 4, 1916, on which this application is an improvement.

One of the principal objects of the present invention is to provide simple and efficient means for causing the general computing operator to be actuated automatically, upon the writing of any figure in the units place in a column, or in other words, upon the setting up of a computing device in the units place in the computing mechanism.

In my co-pending application patented October 26, 1915, No. 1,157,884, I have provided automatic means of a pneumatic type for actuating the operator of the computing mechanism to compute automatically at the end of a number, thus obviating the chance of the operative forgetting to actuate the operator for this purpose. In this application I have illustrated electrical means for actuating the operator and I control the same in the same manner as in my above mentioned patent. That is to say I depend on the conjunctive action of the typewriting or imprinting mechanism, the carriage by its position, and the computing mechanism, to control the drive or actuation of the operator.

In the preferred form of the invention, I employ a constantly running motor, as set forth in pending application No. 596,451, filed December 9, 1910; and this motor, whenever any key is operated to write in the units place in a column, is caused to be connected up to the general operator of the computing machine to reciprocate the same, and thereby effect the desired setting of the computing wheels. Said operator is shown in said application 596,451 as of a reciprocating type, and a rotatable member is connected thereto by a crank, so that one rotation of said member will effect a complete reciprocation of the general operator. This rotatable member is connectible by a clutch to said constantly running motor. The clutch is normally open.

Preferably the clutch tends normally to close, but it is provided with a restraining device which holds it open; and in order to release said restraining device, I preferably provide a power-driven releaser, which, however, is normally disconnected from said restraining device, but at the operation of the typewriting machine at the required point, is automatically connected to said restraining device to release it and permit the clutch to close.

A connection extends from the key-controlled mechanism of the typewriting machine to said clutch, to effect the closing of the same automatically at the desired point in the line of writing, which point is when the last figure in a number, that is the one in the units column has been struck. Upon the carriage of the typewriter, there is mounted a wiper, cam or tappet, which at each step of the carriage, whenever computation is begun, operates one of a set of jacks, whereby is determined the denomination of the computing device to be set by the next depression of a typewriter key. An interponent is provided which is normally out of cooperative relation with the universal bar actuated by all of the typewriting keys, and especially the numeral keys, but adapted to be brought into cooperative relation with said universal bar when a numeral key is struck at a time corresponding to the imprinting of a character in the units column. The interponent may be controlled by the carriage according to the position thereof through the actuation of the computing jack.

corresponding to the units column by the tappet on the carriage.

In the accompanying drawing,

Figure 1 is a side elevation partly in section of an Underwood typewriter combined with a computing machine of the Hanson type, and showing the present improvements applied thereto, the parts being in normal positions and certain devices omitted for the sake of clearness.

Figs. 2 and 3 are fragmentary views of portions of the mechanism taken in side elevation similar to Fig. 1, but showing the mechanism in its actuated position with the interponent opposed operatively to the universal bar corresponding to the instant of actuation of a units jack at the striking of a figure in the units column.

Fig. 4 is a fragmentary perspective view showing the general arrangement of the co-operating elements embodied in this invention.

Fig. 5 is a fragmentary sectional view in side elevation, parts being broken away along different lines from that shown in Fig. 1 to disclose elements concealed in Fig. 1.

A continuously running electric or other motor 1 is provided with a main shaft 2, the latter connected to a shaft 3 by means of a safety friction clutch. This clutch may comprise a disk 5 having a hub 4 keyed to the shaft 2, a friction disk 6 being loose on said hub; another friction disk 7 being confined between disks 5 and 6. An arm 8 fast on shaft 3 is bent over at 9 to be engaged and driven by a lug 10 on disk 6. A compression spring 11 is coiled around the hub 4, and adjusted by a nut 12 to determine how much of a load the clutch will carry without slipping.

A rack 13, forming part of a rack frame, is movable forwardly and backwardly in the base of the adding machine, and performs the final portion of the computing operation. This rack frame is reciprocated intermittently by the constantly rotating shaft 3, by means of a clutch mechanism; said rack frame being connected to a crank shaft to be driven thereby, and the crank shaft being connected by a worm gearing to said shaft 3, as will presently be set forth.

Upon the rack frame is secured a yoke or carrier 14, in engagement with which is the upper end of an arm 15, provided on a cross head 16, which moves forwardly and backwardly, or from left to right and return at Fig. 5, so as to reciprocate said rack frame 13; said cross head being carried on a horizontal slide 17, which works in bearings 18 on a casing 19. This slide is reciprocated by means of a crank 23, fixed on a horizontal shaft 24; said crank carrying a slide block 26, working in a groove 27 in the cross head.

Loose on shaft 24 is a worm gear 30, meshing with a worm 31, the latter fixed on shaft

3, so that the worm wheel 30 is constantly rotating.

The worm wheel 30 is connectible to shaft 24 to turn the same whenever it is necessary to reciprocate the rack frame 13 to complete a computing operation; and at the conclusion of said reciprocation, said worm wheel 30 is automatically disconnected from the shaft 24, and the latter comes to a stop, while the motor 1 continues to rotate.

Fixed to shaft 24 is a cup member 32 of a clutch; and fixed to the hub of worm gear 30 is a collar 33. Running on this collar and adapted to engage the cylindrical inner face of the clutch cup 32, is a gripping ball or roll 34; said roll occupying a pocket 35 in the clutch cup, and rolling on an inclined floor 35' thereof, so that relative movement of the clutch cup and collar 33 in one direction will cause said members to be clutched together by the roll, while relative movement in the opposite direction will produce the opposite effect, so as to permit independent rotation of the gear 30.

The clutch roll is shiftable between gripping and releasing positions in the pocket 35 by means of an annular disk or ring 36, which rides loosely on the collar 33 within cup 32, and which is cut away at one place to receive the roll 34, so as to engage the roll 34 on both sides thereof. Rotation of disk 36, therefore, shifts the roll. Against said disk 36 bears one end of a compression spring 38, which is confined within a pocket 37 formed in said disk; the other end of said spring bearing against a stop 39 secured to the inner side of the clutch cup. The pocket 37 is of sufficient length to permit a movement of the disk 36 without interference from the stop 39. The spring tends to turn the disk 36 with the roll 34 in a direction to lock together the clutch cup with the bearing collar to cause shaft 24 to rotate with gear 30. In other words, said spring tends normally to close the clutch. Normally, however, said disk 36 is restrained from causing the roll to bind; or in other words, said disk is normally held in clutch-releasing position.

For this purpose, there is provided a trip pin or latch 40, normally in engagement with a lug 41 provided upon releasing disk 36, said lug projecting through an opening in the clutch cup. When shaft 24 is to be clutched to the gear 30, the latch 40 is raised to release lug 41, whereupon spring 38 throws disk 36, together with roll 34, thus locking the clutch cup and the shaft 24 to the rotating worm gear 30. The pin 40 is automatically dropped again into the path of lug 41, so that at the completion of a single rotation of the shaft 24, the latter is again unclutched from the worm gear 30.

The rack frame 13 is caused to reciprocate after the numeral keys of the type-

writer have been operated to set up a number. This rack frame operates to turn the computing wheels to different extents, depending upon the key operated. It is necessary, therefore, in some cases, for the described clutch to operate after each number is written on the typewriter; and while the present improvement relates particularly to means for securing such operation automatically, or without attention on the part of the operator, still I will first describe means whereby the operator may depress a special key to operate said clutch, and cause the reciprocation of the rack frame; this mechanism being substantially shown in said application No. 596,451. Said key is designated as 42, and is mounted on a stem 43, pivoted at its lower end to a lever 44, fulcrumed at 45 upon the machine frame. Said lever 44, in turn, depresses a cross lever 46, which is pivoted at 47 to the framework, and at its other end engages a notch 48 formed in the top of the trip pin or latch 40, so as to cause or control the up and down movement of said latch, whereby the clutch is caused to close and open. The lever 46 is provided with an adjustable end or arm 50, upon which the key lever 44 bears; this part 50 being adjustable by screws 52, thereby securing accuracy of adjustment and movement of the clutch-controlling mechanism.

Depression of the key 42 carries down the lever 44, the latter rocks the lever 46 about its fulcrum 47, the other end of the lever lifting the latch 40 away from the clutch lug 41. The operator immediately releases the key 42, which is returned to normal position by a spring 54. The movement of the key is limited by a pin 55 within a slot 56 in the key stem. The lever 46 has a returning spring 57.

The typewriter includes the usual set of type-operating keys, including alphabet keys and also including numeral keys 88 mounted on lever 88^a and connected by bell cranks 89 to type bars 90, which are thrown back against a platen 91 mounted on a carriage 92. The carriage is power-driven, as usual, and has a rack 97 meshing with a pinion 86, connected with an escapement wheel 85, the latter controlled by dogs 84, operated by a universal bar 83, which is actuated by the type bars, so that whenever any type key is actuated, the carriage 92 is caused to feed a letter space.

Fastened at the back of the carriage 92, are brackets 93, carrying a rack 94, to receive adjustable cams or tappets 95 which act as denomination selectors. Whenever any tappet, during the travel of the carriage, passes beneath the set of jacks 96, it raises the forward ends of the jacks in succession, turning each on its pivot 97, and depressing its rear end to press down the corresponding

one of a set of wires 98. These wires are connected at their lower ends to levers 99 on a fulcrum rod 100.

Each lever 99 raises one of a set of linkages 101, each linkage having a pin 102 to lift the rear end of a rack 103, the forward end of which meshes with a pinion 104 connected to a computing wheel 105. Each rack carries a set of pins 106, and one of these is depressed by the operated type key 88; each key having a stem 110, for this purpose, to depress a crank 112, fast to a shaft 113, which is connected to a linkage 114, to depress one of the pins 106 upon the lifted rack bar 103; there being one linkage 114 for each key, each linkage being in position to depress a corresponding pin 106 on whichever rack bar is lifted, as set forth in the above mentioned pending applications. After the keys 88 are manipulated to write a number, and the corresponding racks 103 accordingly elevated as the paper-carriage feeds along, and certain pins 106 thereon depressed, there must be caused a reciprocation of the rack frame 13. This frame usually includes a pair of arms 115 connected by a transverse horizontal bar 116, which is in position to engage all the displaced pins 106, and to give corresponding forward endwise movements to their racks 103, thereby turning the computing wheels 105 accordingly; the return movements of the racks not turning said wheels, however, because of a pawl-and-ratchet connection (not shown) between said wheels and their drive pinions 104. Pinions 116^a meshing with racks 13, are also in mesh with segments 116^b fixed on rock-shaft 116^c.

Up to this time I have described how the connection of the electro-motive means, shown in the form of an electric motor, to the operator may be manually controlled. As has been stated above, it is highly desirable to control the same automatically to avoid the omission of the operation of the same. For this purpose, means may be utilized to connect the electro-motive means with the operator by the conjunctive action, both combined and co-operative of the keys and carriage, and certain parts of the computing mechanism. In this instance, there is shown an interponent or rod 123, normally out of co-operative relation with the universal bar 83, but adapted to be brought into co-operative relation therewith, so as to be actuated thereby. This interponent or bar 123, is normally held out of alignment with the universal bar 83 by a link 124, which is shown as suspended from the rear portion of the units jack. The interponent 123 is shown as being slidingly and pivotally supported by a bracket 125 by passing through an opening therein, but any other means may be used for this purpose.

The forward end of the interponent 123 is

is seen to extend through the loop 126 forming a pin and slot connection with a bell crank lever 127, of which the loop 126 forms one arm. It will be seen that the bell crank lever 127 may be operated from the interponent 123 when the latter is actuated by the universal bar 83 through the intermediary of a lug 128 on the interponent 123 shown in the form of adjustable nuts having a screw-thread connected with the interponent 123 whereby the effective throw of the bell crank may be varied. Another arm of the bell crank 127, indicated at 129, may be operatively connected to a lever 130, pivoted at 131, by means of a link 132. It will be seen that the forward end of the lever 130 rests on the key 42 so as to actuate the same. A spring 133 may be used, if desired, to return the links and levers together with the interponent, back to their original ineffective position. It is to be understood that the interponent 123 might be more directly connected to the controlling mechanism of the connection between the electric motor and the operator 13. However, the mechanism just described is sufficient to illustrate the spirit of this invention.

It will be seen that when one of the numeral keys is struck, at a time when the carriage occupies a position corresponding to that in which a figure will be struck in the units column, the units jack will have been raised at its forward end through the intermediary of the carriage tappet, or cam 35 whereby the rear end of the units jack will have been lowered a sufficient distance to permit the interponent 123 to fall in juxtaposition to the universal bar 83 whereby the movement of said universal bar will actuate said interponent, and thus through the intermediary of the bell crank lever 127, the key 42 and the connected mechanism, throw the operator 13 into operative connection with the motor 1 through the clutching mechanism, whereby said operator will be reciprocated so as to carry the numerals on the computing mechanism which have been previously set up by certain parts of the computing mechanism above described. 50 In other words, it may be said that the action of the imprinting or recording mechanism, the work sheet carrying carriage and certain parts of the computing mechanism must be conjunctive and at a time corresponding to the imprinting and setting up of the figure in the units column, in order to cause the actuation of the computing mechanism, to add or subtract the numeral just written, by connecting the electro-magnetic means shown in the form of an electric motor in driving relation with the computing mechanism through the intermediary of the clutching mechanism. This means that in such operation as tabulating, the general

operator remains unaffected by movements of the typewriter carriage.

Variations may be resorted to within the scope of the invention, and parts of the improvements may be used without others.

Having thus described my invention, I claim:

1. In a combined typewriting and computing machine, the combination with a plurality of numeral keys, of computing mechanism, actuating means for said computing mechanism, connections between said actuating means and said computing mechanism normally ineffective, an operating key for making said connections effective, and means acting as an intermediary between said numeral keys and said operating key whereby said operating key can be controlled by said numeral keys.

2. In a combined typewriting and computing machine, the combination with a plurality of numeral keys, of computing mechanism, actuating means for said computing mechanism, normally ineffective connections between said actuating means and said computing mechanism, an operating key for controlling said connections, a carriage, and means acting as an intermediary between said numeral keys and said operating key, whereby said operating key can be controlled from said numeral keys, said last-mentioned means being normally ineffective and brought into effective position by the movement of said carriage to a predetermined point in its travel.

3. The combination with a computing mechanism, of numeral keys for actuating said computing mechanism, a manually operable special key for inciting certain parts of said computing mechanism to action, a typewriter carriage, type bars actuated by said keys to coöperate with said carriage, and means dependent on the conjunctive action of one of said numeral keys and said carriage to operate said special key.

4. In a combined typewriting and computing machine, the combination with computing mechanism, of a typewriter carriage, numeral keys for controlling said carriage and for setting up numbers in said computing mechanism, driving means for said computing mechanism, a special key for determining the operation of said driving means, and automatic means for enabling any of the numeral keys, upon setting up digits in units place in a number, to operate said special key.

5. The combination with a traveling carriage, computing mechanism, and numeral keys, of driving means for said computing mechanism, a special key for starting said driving means, and automatic means under the joint control of said carriage and said numeral keys for operating said starting

- key; said automatic means including an interponent between said carriage and said numeral keys and actuated by the latter, and connections between said interponent and said starting key.
6. The combination with a traveling carriage, computing mechanism, and numeral keys, of driving means for said computing mechanism, a special key for starting said driving means, and automatic means under the joint control of said carriage and said numeral keys for operating said starting key; said automatic means including an interponent between said carriage and said numeral keys which is operated by the latter and is normally ineffective with relation thereto, but is rendered effective by said carriage, and connections between said interponent and said starting key.
7. The combination with a traveling carriage, computing mechanism, and numeral keys, of driving means for said computing mechanism, a special key for starting said driving means, and automatic means under the joint control of said carriage and said numeral keys for operating said starting key; said automatic means including an interponent between said carriage and said numeral keys and actuated by the latter, a lever bearing upon said starting key, and

connections between said interponent and said lever for operating said lever.

8. The combination with a traveling carriage, computing mechanism, and numeral keys, of driving means for said computing mechanism, a special key for starting said driving means operable manually at any point in the traverse of the carriage, and automatic means under the joint control of said carriage and said numeral keys for operating said starting key at a predetermined point in the traverse of the carriage.

9. The combination with a traveling carriage, computing mechanism, and numeral keys, of driving means for said computing mechanism, a special key for starting said driving means operable manually at any point in the traverse of the carriage, and automatic means for operating said starting key at a predetermined point in the traverse of the carriage; said automatic means including an interponent between said carriage and said numeral keys and actuated by the latter, and connections between said interponent and said starting key.
